(57) **ABSTRACT**

'Vieyra' is a new Rainier-type sweet cherry variety distinguished by its early-maturing fruit.

3 Drawing Sheets

1

Genus and species: *Prunus avium*.
Variety denomination: 'Vieyra'.

BACKGROUND AND SUMMARY OF THE
VARIETY

The new sweet cherry variety 'Vieyra' was discovered by the inventor in 2008, in a 'Rainier' cherry (not patented) orchard near East Wenatchee, Wash. 'Vieyra' is believed to be a whole-tree mutation of 'Rainier', distinguished by its early maturity and larger and redder fruit as compared to 'Rainier'. In 2009, after observing the distinguishing characteristics again, the inventor budded scionwood cuttings of the 'Vieyra' tree on 'Mazzard' rootstock (not patented) near East Wenatchee, Wash., to produce 18 nursery trees for further observation. The test trees were planted in the spring of 2011 near East Wenatchee, with additional test trees planted the following year. 'Vieyra' cherry has been found to exhibit its distinctive characteristics through successive asexually propagated generations.

'Vieyra' was initially selected for, and is distinguished by, its early-maturing fruit. The 'Vieyra' cherry ripens 8 to 10 days earlier than 'Rainier' and exhibits a brighter red over-color as compared to 'Rainier'. It has also been observed that the trunk lenticels of 'Vieyra' are larger and more prominent than those of 'Rainier'.

As compared to the fruit of the 'Doty' cherry tree (U.S. Plant Pat. No. 13,951) 'Vieyra' cherries are larger, with a 40 brighter overcolor and whiter flesh.

2

'Vieyra' cherries have a shorter stem and tighter seed cavity than either 'Doty' or 'Rainier' cherries.

BRIEF DESCRIPTION OF THE PHOTOGRAPHS

5 The accompanying photographs of six-year-old trees of the claimed variety were obtained in 2017 near East Wenatchee, Wash.
10 FIG. 1 shows the fruit and leaves of the claimed variety;
FIG. 2 shows blossoms of the claimed variety; and,
FIG. 3 shows a second generation tree of the variety, in bloom.

15 The colors of these photographs may vary with lighting conditions. Color characteristics of this new variety should therefore be determined with reference to the observations described herein, rather than from the photographs alone.

DETAILED BOTANICAL DESCRIPTION

20 The following detailed botanical description is based on observations of second-generation trees of the variety, planted in 2011 and grown on 'Mazzard' rootstock (not patented) on a V-trellis system with 5-foot spacing. Observations were recorded during the 2017 growing season near 25 East Wenatchee, Wash. The characteristics described will vary somewhat depending upon cultural practices and climatic conditions, and can vary with location and season. Quantified measurements are expressed as an average of measurements taken from a number of individual plants of the new variety. The measurements of any individual plant, or any group of plants, of the new variety may vary from the stated average. Colors are described with reference to the Munsell Book of Color.

Tree:
35 *Vigor*.—Vigorous.
Habit, shape.—Columnar.
Density.—Moderate, average for sweet cherry trees.
Height.—5 m.
Trunk diameter (at 30 cm above the graft).—20 cm.
Bark texture.—Smooth with vertical striations and horizontal lenticels.

<i>Bark coloration.</i> —7.5 R 2/4 (reddish brown), similar to 'Rainier'.	Style:
<i>Lenticel length.</i> —1 to 3 cm.	<i>Length.</i> —8 mm.
<i>Lenticel color.</i> —2.5 R 3/4 (reddish brown).	<i>Color.</i> —2.5 GY 6/6 (light green).
<i>Lenticel quantity.</i> —More numerous than 'Rainier'.	Ovary:
Branch (fruiting branches located at around 1 m above the graft union):	5 <i>Length.</i> —1 mm.
<i>Diameter.</i> —40 mm.	<i>Color.</i> —2.5 GY 6/6 (light green).
<i>Length.</i> —About 2 to 3 meters before pruning.	Stamens:
<i>Crotch angle.</i> —90°.	<i>Quantity.</i> —Average of 24.
<i>Bark color.</i> —10 YR 3/2 (medium brown); 10 YR 6/2 (medium tan).	<i>Anther size.</i> —0.5 to 1 mm.
<i>Bark texture.</i> —Smooth with prominent lenticels, typical of 'Rainier' and 'Doty'.	<i>Anther color.</i> —5Y 6/6 (yellow/brown).
<i>Lenticel length.</i> —1 to 3 mm.	<i>Filament size.</i> —Diameter 0.5 mm, length 10 to 15 mm.
<i>Lenticel color.</i> —10 YR 6/6 (yellowish tan).	<i>Presence of pollen.</i> —Abundant.
<i>Lenticel quantity.</i> —Scattered, averaging 1 per cm ² .	<i>Color of pollen.</i> —7.5 Y 7/10 (yellow).
One year old shoot:	Sepals:
<i>Length.</i> —32 to 36 cm.	<i>Quantity.</i> —5.
<i>Color.</i> —5 GY 6/6 (light green).	<i>Color.</i> —2.5 GY 7/6 (light green).
<i>Pubescence.</i> —Glabrous.	<i>Shape.</i> —Oblong conical.
<i>Diameter.</i> —6 mm.	<i>Apex.</i> —Obtuse to acute.
<i>Internode length.</i> —3.5 to 5 cm.	<i>Base.</i> —Aequilateral.
<i>Lenticel length.</i> —1 mm.	<i>Margin.</i> —Smooth.
<i>Lenticel color.</i> —10 YR 7/2 (grey green).	<i>Length.</i> —5 mm.
<i>Lenticel quantity.</i> —3 per cm ² .	<i>Width.</i> —4 mm.
Flower buds:	Leaves:
<i>Quantity per spur.</i> —3 to 5.	<i>Length.</i> —10 to 20 cm, average 18 cm.
<i>Shape.</i> —Elongate, conic.	<i>Width.</i> —6 to 8.5 cm, average 7.5 cm.
<i>Length.</i> —15 mm.	<i>Blade margin.</i> —Irregularly serrate.
<i>Diameter.</i> —5 mm.	<i>Leaf shape.</i> —Obovate.
<i>Color.</i> —10 R 3/4 (brown with a reddish tinge).	<i>Apex shape.</i> —Acuminate.
Flowers:	<i>Base shape.</i> —Oblate to tapering.
<i>Diameter of fully open flower.</i> —30 to 40 mm.	<i>Texture.</i> —Upper surface smooth; veins pronounced on underside.
<i>Depth of fully open flower.</i> —25 mm (not including pedicel).	<i>Attitude in relation to shoot.</i> —Typical of sweet cherries.
<i>Relative position of petal margin.</i> —Overlapping until fully open.	<i>Color of upper surface.</i> —5 GY 3/4 (dark green).
<i>Pedicel length.</i> —20 mm.	<i>Color of lower surface.</i> —10 GY 4/4 (medium green).
<i>Pedicel diameter.</i> —1.5 mm.	Petiole:
<i>Pedicel color.</i> —5 GY 5/10 (medium green).	<i>Length.</i> —2.5 to 3.5 cm.
<i>Number of flowers per cluster.</i> —3 to 5.	<i>Diameter.</i> —2 mm.
<i>Date of first bloom.</i> —2 days before 'Doty' and 'Santina' (not patented).	<i>Color.</i> —10 GY 6/6 (medium green).
<i>Date of full bloom.</i> —2 days before 'Doty' and 'Santina'.	40 <i>Glands.</i> —2 present. Oblong, 1.5 to 2 mm in length. Bi-colored 10Y 6/6 (grayish yellow green) and 2.5 Y 6/4 (tan), positioned in a groove about 3 cm from base of leaf petiole and about 2 mm below leaf blade.
Petals:	Fruit:
<i>Number per flower.</i> —5.	<i>Quantity per cluster.</i> —3 to 5.
<i>Length.</i> —15 mm.	<i>Diameter.</i> —25 to 30 mm, slightly larger than 'Doty', which runs 25 to 28 mm.
<i>Width.</i> —14 mm.	<i>Length.</i> —21 to 25 mm.
<i>Petal shape.</i> —Round obovate.	<i>Weight.</i> —Average 1.25 g per fruit, slightly larger than 'Doty', which averages 1.2 g per fruit.
<i>Apex.</i> —Round.	<i>General shape in profile.</i> —Reniform
<i>Base.</i> —Acute.	<i>Shape of pistil end.</i> —Rounded to slightly indented.
<i>Margin.</i> —Smooth with some notching.	<i>Depth of stalk cavity.</i> —3 mm; 1 mm deeper than 'Doty' with more pronounced shoulders.
<i>Coloration of upper surface.</i> —White.	<i>Diameter of stalk cavity.</i> —8 to 12 mm; up to 4 mm wider than 'Doty'.
<i>Coloration of lower surface.</i> —White.	<i>Depth of suture.</i> —Less than 1 mm.
Pistil:	<i>Skin thickness.</i> —Thicker than 'Doty'.
<i>Length.</i> —10 mm.	<i>Skin texture.</i> —Smooth.
<i>Diameter.</i> —0.5 mm.	<i>Ground color.</i> —7.5 Y 8/12 (yellow).
<i>Color.</i> —2.5 GY 8/8 (pale green).	<i>Overcolor.</i> —5 R 6/10 (light red) to 5 R 4/14 (dark red).
Stigma:	<i>Pattern and intensity of overcolor.</i> —Intense 80% to 90% overcolor, as compared to 70% overcolor on 'Doty'.
<i>Size.</i> —1 mm.	<i>Taste.</i> —Complex flavor with pleasant bitterness.
<i>Color.</i> —7.5 Y 8.5/8 (light yellow).	

US PP30,865 P2

5

6

Stalk:

Length.—28 to 32 mm; shorter than 'Doty'.*Diameter*.—1.5 mm.*Color*.—2.5 GY 6/6 (light to medium green).

Flesh:

Flesh texture.—Firm and crisp.*Fibers*.—None detected.*Aroma*.—Slightly fruitier than 'Doty'.*Juiciness*.—Juicy.*Soluble solids*.—19.4 to 20.5° Brix; compare to 16 to 10 16.8° Brix for 'Doty'.*Acidity*.—Medium.*Flesh color*.—5 Y 9/4 (cream).*Juice color*.—5 Y 9/2 (pale light yellow).

Stone:

Length.—10 mm.*Diameter*.—7 mm.*Shape*.—Oblong.*Color*.—2.5 Y 7/8 (brownish yellow).*Surface texture*.—Smooth.*Adherence to flesh*.—Semi-freestone.*Tendency to split*.—Similar to 'Rainier' in area tested.

Harvest:

Harvest date.—8 to 10 days before 'Rainier'.*Number of picks*.—1.*Productivity per tree*.—20 to 21 kg per tree.*Bearing*.—Annual.*Chilling requirement*.—Similar to 'Rainier'.*Cold hardiness*.—Hardy in area tested (North Central Washington, USDA Zone 5).

Disease resistance/susceptibility: None noted; similar to 'Rainier'.

Market use.—Fresh.*Keeping quality*.—Similar to 'Rainier'.*Shipping quality*.—Similar to 'Rainier'.

The invention claimed is:

1. A new and distinct variety of cherry tree, substantially as illustrated and described herein.
